US00D624559S

(12) **United States Design Patent**
Chung

(10) **Patent No.:** **US D624,559 S**
(45) **Date of Patent:** **** Sep. 28, 2010**

(54) **DVD PLAYER**

(75) Inventor: **Yeon-Moo Chung**, Seoul (KR)

(73) Assignee: **Samsung Electronics Co., Ltd.**, Suwon, Kyunggi-do (KR)

(**) Term: **14 Years**

(21) Appl. No.: **29/348,330**

(22) Filed: **Dec. 22, 2009**

(51) **LOC (9) Cl. 14-01**

(52) **U.S. Cl. D14/502**

(58) **Field of Classification Search** D14/496, D14/498–511, 157, 167–168, 188, 197–198, D14/257, 258; 360/99.02, 99.07; 369/75.11, 369/75.21, 77.11, 77.21; 720/601, 612, 619, 720/649, 655; 455/344, 347–351

See application file for complete search history.

(57) **CLAIM**

The ornamental design for a DVD player, as shown and described.

DESCRIPTION

FIG. 1 is a top front perspective view of a DVD player showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

1 Claim, 3 Drawing Sheets
